UNITED STATES PATENT OFFICE.

ARTHUR E. LINDNER, OF WILMINGTON, DELAWARE, ASSIGNOR TO JULIUS KAYSER, OF NEW YORK, N. Y.

CIRCULAR-WARP-KNITTING MACHINE.

SPECIFICATION forming part of Letters Patent No. 606,351, dated June 28, 1898.

Application filed July 21, 1897. Serial No. 645,345. (No model.)

To all whom it may concern:

Be it known that I, ARTHUR E. LINDNER, a citizen of the Empire of Germany, residing in Wilmington, in the county of New Castle and 5 State of Delaware, have invented certain new and useful Improvements in Circular-Warp-Knitting Machines, of which the following is a specification.

This invention relates to certain improvements in circular-warp-knitting machines of 10 that class by which a knitted warp fabric known as "Milanaise" is produced at a considerably-greater speed and at smaller expense than by the ordinary straight-warp-knitting machines heretofore in use.

The invention consists, mainly, of a circular-warp-knitting machine which comprises a series of reciprocating needles, a vertically-reciprocating presser-ring above said needles, a vertically-reciprocating sinker-ring below the needles, horizontally-reciprocating sinkers, and two sets of thread-guides to which an intermittent or step-by-step rotary motion in opposite directions to each other is 25 imparted.

The invention consists, further, of mechanisms by which the required motion is imparted to the different parts described by means of cams from a main and auxiliary 30 driving-shaft, as will be fully described hereinafter and finally pointed out in the claims.

In the accompanying drawings, Figure 1 represents a plan view of my improved circular-warp-knitting machine, a part being 35 broken off. Fig. 2 represents a vertical central section of the same on line 2-2, Fig. 1, drawn on the same scale as Fig. 1. Fig. 3 represents a horizontal section on line 3-3 of Fig. 2. Fig. 4 represents a vertical central 40 section through the upper part of the machine, and more especially through the needle-plate, presser-ring, and sinker-ring, showing some of the mechanisms for actuating the needles, presser-ring, and sinkers. Fig. 5 represents a plan view of one-half of the 45 needle-plate, showing a portion of the series of reciprocating needles, the guide-grooves therefor, the needle-carriers, and the operating mechanism for the needle-carriers. Fig. 50 6 represents a bottom view of one-half of the sinker-ring with its actuating mechanism.

Figs. 7, 8, and 9 are vertical detail sectional views showing the different positions of the thread-guides relatively to the needles, presser-ring, and sinkers during the formation 55 of the stitches. Fig. 10 represents a vertical transverse section through the main guide-ring, the thread-guide-carrier rings, and pawl-carrier rings, showing the thread-guides and their supporting-plates in side elevation. 60 Fig. 11 represents a plan view of one section of the supporting-plate for the upper thread-guides. Fig. 12 represents a plan view of a section of the supporting-plate of the lower thread-guides. Fig. 13 represents a plan 65 view of the main guide-ring, pawl-carrier rings, and thread-guide-carrying rings. Fig. 14 represents a detail elevation of the pattern-wheel mechanism by which intermittent motion in opposite directions is alternately imparted to the pawl-carrier rings. Fig. 15 represents a detail plan view of the pattern-wheels by which said motion is imparted, showing the main guide-ring removed. Fig. 16 represents a vertical radial section through 70 the main guide-ring and through the thread-guide-carrier rings and pawl-carrier rings disposed therein and through the top ring, showing the supports for said main guide-ring in connection with the pattern mechanism for operating the pawl-carrying rings. Fig. 17 represents a detail section showing the spline connection of the transmitting ratchet-wheel with the shaft of the pattern-wheels. Fig. 18 represents a detail plan view 80 of the pattern-wheel mechanism. Fig. 19 represents a detail plan view of an oscillating elbow-lever interposed between the retracting-cam and the connecting-rod of the pattern-wheel mechanism. Fig. 20 represents a 85 detail plan view of the mechanism for actuating the bobbin-rings. Figs. 21 and 22 are respectively a plan view and a side view of one of the needle-carriers. Fig. 23 represents a perspective view of the group of needles in 90 each needle-carrier. Fig. 24 represents a sectional side elevation of one of the sinker-carriers. Fig. 25 represents a perspective view of the group of sinkers in each sinker-carrier. Figs. 26 to 31 are diagrams showing the successive operations of the needles, presser-rings, sinkers, and thread-guides required for 95 100

forming a stitch. Fig. 32 represents an elevation, on a greatly-enlarged scale, of a fragment of the fabric, a transverse section of the front end of one of the needles just back of its barb, and end elevations of the thread-guides, the needle being in its outermost position and the thread-guides being in the positions which they assume above the needle after having shifted horizontally, the threads to form the next loop being crossed over the upper surface of the shank of the needle. Fig. 33 represents, also on a greatly-enlarged scale, an elevation of a fragment of the fabric, the barbed end of the needle, and the ends of the thread-guides, the needle being in the position which it assumes after being partially drawn inward with its barb closed over the crossed threads and the previously-formed loop riding over the top of the barb, the thread-guides being in their lowered position below the needles. Fig. 34 is a diagram representing on an enlarged scale the method of forming the fabric in connection with a number of needles, the parts being in the same relative positions as in Fig. 33.

The same letters and numbers of reference indicate corresponding parts in all the figures.

Referring to the drawings, A represents the circular bed-plate of my improved circular-warp-knitting machine; A', four upright standards which are rigidly attached to said bed-plate and which serve as supports for the brackets a a' , on which the lower bobbin-carrying ring B is supported, while the upper ends of the standards support a ring-shaped plate A², on which the upper bobbin-carrying ring B' is supported. The upright standards A' are further provided below the top ring A², that binds the standards rigidly together, with suitable bracket-bearings, in which some of the auxiliary motion-transmitting shafts are supported. At the center of the bed-plate A are arranged four upright standards A³, which are located radially in line with the outer standards A', and which are curved inwardly at their upper parts, so as to support the stationary needle bed-plate C, the bearings for a central vertical motion-transmitting shaft S', and to four shorter standards A⁶, which are curved at their upper ends, by which the bearings for the transmitting-shafts, by which motion is imparted to the vertically-reciprocating presser-ring D, are supported. On outwardly-projecting brackets a^2 and a^3 of the upright standards A³ are guided vertically-reciprocating rods e, which support at their upper ends the sinker-ring E, on which the sinkers are supported, said rods e receiving vertical motion from grooved cams e' on the main driving-shaft S, said shaft extending between two diametrically opposite outer and inner standards A³ and being supported in suitable journal-bearings of the same. At right angles to the driving-shaft S are arranged two shorter driving-shafts S² S³, which are supported in suitable bracket-bearings attached to the bed-

plate A, and which are likewise provided with grooved cams e', as shown in plan view in Fig. 3, that actuate the sinker-ring by other intermediate rods e and the cams e'. The inner ends of the rotary shafts S² S³, as well as the step-bearing of the vertical shaft S', are supported in a yoke-shaped bracket A⁵. (Shown in Fig. 2.) Rotary motion is transmitted from the main driving-shaft S by bevel-gears 10, 11, and 12 to the rotary shafts S² S³ and by larger bevel-gears 13 and 14 to the vertical shaft S', as shown clearly at the lower part of Fig. 2.

The needle-carrying mechanism. — The needle bed-plate C is supported in stationary position on the inner standards A³ and provided with an exterior ring C', in which radial grooves are arranged for guiding the shanks of the individual sections of the needle-carriers. Concentric with this grooved guide-ring is arranged a second interior ring C², which is likewise provided with radial grooves, but of a smaller number—for instance, one groove for every six grooves in the exterior guide-ring. The interior ring C² and its grooves serve for guiding the shanks of the needle-slides C³ for operating a group of needle-carriers 16, as shown in Fig. 5 at the left-hand side, while the right-hand side of Fig. 5 shows the grooved interior and exterior guide-rings with needle-carriers and actuating-slides removed. Each needle-carrier is provided with, say, ten needles 15, as shown in Figs. 21 to 23, the shanks of the needles being set into recesses of the carriers and secured by suitable cap-plates in the same. The head of each T-slide C³ is pivotally connected with the shanks of six needle-carriers; but it is obvious that a larger or smaller number may be connected with said T-slide, according as the machine is made larger or smaller in size, for knitting tubular fabrics of greater or smaller diameter. The inner ends of the radial shanks of the T-slides C³ are connected by pins with bell-crank levers C⁴, which are fulcrumed at their apices to the raised portions of the inner ring C², as shown in Fig. 5, while the inner ends of said fulcrumed bell-crank levers are engaged by pins of a rotary reciprocating ring C⁵, which is guided in a circular groove of the needle bed-plate and which is actuated by a fulcrumed lever C⁶, that is pivoted to a point of the ring C⁵, fulcrumed to the central depressed portion of the bed-plate C, the inner arm of said fulcrum-lever C⁶ being provided with an antifriction-roller that is engaged by a cam-groove at the under side of a cam C⁷, attached to the vertical central shaft S'. The rotary motion of the cam C⁷ imparts by its eccentric cam-groove an oscillating motion to the fulcrumed lever C⁶, which imparts thereby rotary reciprocating motion to the actuating-ring C⁵. This motion is again transmitted by the fulcrumed elbow-levers to the T-piece C³ and by them to the needle-carriers, so that in this manner the entire series of needles

arranged on the circular bed-plate receive simultaneously a radially-reciprocating motion at each full rotation of the center shaft. The needles 15 employed are the well-known 5 "bearded" needles, having grooves in their shanks for receiving the beard of the needles when they are pressed down by the presser, as well known in knitting-machines.

Above the beards of the needles is arranged 10 a circular presser-ring D, as shown in Figs. 2 and 4, which ring is attached by screws to an inverted-bell-shaped presser-ring carrier D'. The presser-ring is preferably arranged in closely-abutting sections, that are applied 15 stationarily to the bell-shaped carrier D' by set-screws 20, which pass through suitable slots 21 in the upper parts of the presser-ring sections, so that the presser-ring can be slightly adjusted in an up-and-down direction. 20 relatively to the beards of the needles. The bell-shaped carrier D' is provided with a central top opening and side openings, so as to decrease its weight, and receives a vertically-reciprocating motion by means of four grooved cams D², which are attached to four radial shafts D³, that are located at right angles to each other, as shown clearly in Figs. 1 and 2. The grooved cams D² engage antifriction-pins D⁵, arranged on slide-blocks D⁴, guided in the 25 short upright standards A⁶, which are attached to the stationary needle bed-plate. The presser-ring carrier is supported at its inner rim on the slide-blocks D⁴ and fastened by screws 22 to the same, so as to prevent any 30 axial motion. On the upper end of the vertical shaft S' and above the needle bed-plate is arranged a smaller bevel-wheel 30 and above the same a larger bevel-wheel 34, the smaller meshing with bevel-wheels 31 and 32 35 of two diametrical shafts D³, while the larger bevel-wheel 34 engages corresponding bevel-wheels on the inner ends of the remaining two shafts D³, that are arranged at right angles to the former, so that all four shafts receive 40 rotary motion and impart thereby the required degree of vertically-reciprocating motion to the presser-ring.

The sinker-ring.—Below the stationary needle bed-plate is arranged the sinker-ring 50 E. This sinker-ring is guided in its vertical movement imparted by the rods e on a circular shoulder e^x on the under side of the needle bed-plate C, as shown in Fig. 4. The sinker-ring E is preferably made of one integral casting and provided at its under side with radial grooves 43 for guiding the shanks E' of the sinker-carriers E², which are shown in Figs. 24 and 25. The shanks of the sinker-carriers are retained in radial grooves at the 55 under side of the sinker-rings by means of cap-plates 40, so as to prevent the dropping of the sinker-carriers. Each sinker-carrier is provided with, say, ten sinkers E³. The sinkers E³ are vertically secured in groups of 60 ten, more or less, in any suitable manner to sinker-carriers e³. These sinker-carriers are secured in vertical position on sinker-slides

E², having shanks E'. The sinker-carriers are preferably adjustable vertically on the sinker-slides. To effect this adjustment, they 70 may be provided with slots 41 and secured to the sinker-slides by screws 42, passing through said slots. The sinker-slides E² are adapted to move radially in an outer series of grooves 43, disposed at close intervals on the under 75 side of the sinker-ring E. T-shaped slides E⁴ are adapted to slide in radial grooves 46 in inner ledge 45 on the under side of the sinker-ring E, an annular channel 44 separating the outer series of radial grooves 43 from the inner series 46. These T-slides E⁴ correspond in shape with the T-slides C³ for the needle-carriers, and six sinkers, more or less, are connected with each T-slide E⁴. A plate 48 on the under side of the inner ledge of the 80 sinker-ring E holds the slides E⁴ in position. These features are best shown in Figs. 6, 24, and 25. The inner ends of the T-slides E⁴ are connected with bell-crank levers 50, that are fulcrumed to studs 51 on the guide-shoulder e^x on the under side of the needle bed-plate C, said studs being of a length to permits sufficient vertical play for said bell-cranks E⁵, so that they are not affected by the vertically-reciprocating motion imparted to the 90 sinker-ring. The inner ends of the fulcrumed bell-cranks E⁵ are connected with pins 52 on a rotary reciprocating ring E⁶, which is guided in a guide-groove on the under side of the needle bed-plate and flush with the same. 100 The required reciprocating motion is imparted to the ring E⁶ by a cam E⁷ on the shaft S' and an intermediate fulcrumed lever E⁸ in the same manner as the motion imparted to the T-slides C³ of the needle-carriers. While 105 the grooved cam C⁷, by which motion is imparted by the needle-carriers, has its cam-groove at its under side, the grooved cam E⁷ is inverted and has its cam-groove on its upper side, said cams being arranged with their 110 grooved portions facing each other, as shown in Fig. 4. The arrangement of the grooved cams C⁷ and E⁷ on the same shaft produces, in connection with the corresponding motion-transmitting mechanisms, the accurate reciprocating motions of the needles and sinkers, 115 section for section, throughout the entire circumference of the needle bed-plate and sinker-ring.

The thread-guides and their actuating mechanism.—In connection with the horizontally-reciprocating needles, vertically-reciprocating presser-ring, and vertically and horizontally reciprocating sinkers are arranged two sets of thread-guides F F' in a circle around 120 the needles, as shown in Fig. 2, said thread-guides being arranged in groups corresponding to the groups of needles and sinkers. The upper thread-guides F are arranged in groups of ten, more or less, held by their 125 shanks in sockets of convex carrier-plates F², which are hinged at their outer ends to plates F⁴, said plates being attached to thread-guide-carrier rings F⁶. The lower thread-guides F'

are also disposed in groups of ten, more or less, which are secured in a shorter carrier-plate F³, disposed under the carrier-plate F² and hinged at its outer end to a plate F⁵, that is secured to the thread-guide-carrier ring F⁷, as shown in Fig. 10. On the pintles of the thread-guide-carrier plates F² F³ are applied helical springs f, by which the carrier-plates are held in their normal position, so that the eyes of the thread-guides are close together, as shown in Fig. 10. When it is desired to pass the thread through the eyes of the thread-guides, they are turned on their hinges up in vertical position against the tension-springs, so that the threading of the eyes is facilitated. The upper carrier-plate F² is supported in position in both directions by stops, the screw-stop f' engaging a center slot 60 of said plate F² when the same is moved in vertical position, and a headed pin-stop f², applied to an inwardly-projecting arm f³, prevents the carrier-plate F² from moving out of its horizontal position. The lower carrier-plate F³ is likewise provided with stop devices, so as to hold it in its two positions. A radial inwardly-extending screw f⁵ binds on the inner edge of the carrier-plate F³ and holds it in horizontal position, and a stop f⁶, that swings on a screw-pivot, serves when turned inwardly to engage the slot f⁴ of the carrier-plate F³ when the same is turned in upright position for threading. The thread-guide-carrier rings F⁶ and F⁷ are guided in the grooved main guide-ring F⁸ by means of a shoulder on the bottom of the same and inwardly-projecting ring-flanges 70 and 71 on the upper edges, so that each carrier thread-guide ring has its circular guideway. The thread-guide-carrier ring F⁶ is provided at the middle portion of its inner face with ratchet-teeth 72, and the thread-guide-carrier ring F⁷ is provided on its outer face with ratchet-teeth 73, which teeth are engaged by pawls pivoted in pairs to two pawl-carrying rings G and G', that are guided at the bottom of the grooved main guide-ring F⁸ between a raised shoulder of the same and the inner faces of the thread-guide-carrier rings F⁶ F⁷. The thread-guide-carrier rings F⁶ and F⁷ are not made continuous, but in detachable sections. The sections of the thread-guide-carrier rings F⁶ F⁷ are provided with outwardly and inwardly projecting angular lugs 75 and 76, respectively, that project over the outer and inner faces of the main guide-ring F⁸, so as to retain said sections in position and prevent any shifting thereof. The sections of the carrier-rings are thereby practically like one entire ring, but with the advantage that the difficulty of subdividing such large rings for the required number of thread-guides is obviated and that thereby any small inaccuracies that may take place are confined only to a small section, but not multiplied and increased over the entire circumference of the guide-rings.

The main guide-ring F⁸ has no motion on

its axis, but receives only a vertically-reciprocating motion by means of four upright supporting-rods F⁹, which are guided in suitable sleeves of the supporting-frame, as shown in Fig. 2, and the slotted portions of which are engaged by cams f⁹ on short horizontal shafts S⁶, which are supported in box-shaped portions A⁴ of the outer standards A'. The short horizontal shafts S⁶ receive rotary motion by bevel-gears from vertical shafts S⁷, that are supported in suitable neck and step bearings of the outer standards A' and rotated by bevel gear-wheels from the main driving-shaft S and the transverse shafts S² S³, as shown in Figs. 2 and 3. As the mechanisms for imparting vertically-reciprocating motion to the main guide-ring F⁸ are applied to four equidistant points of the same, the up-and-down motion of the same is perfectly steady and reliable, so that the thread-guides are moved from a point above and below the needles, and vice versa, as required, for the proper formation of the stitches.

The pawls for actuating the thread-guide-carrier rings F⁶ and F⁷ are disposed in pairs on the pawl-rings G and G', the several pairs of pawls marked g g' being pivoted on the outer pawl-ring G and the several pairs comprising the pawls g² and g³ being pivoted on the inner pawl-ring G'. The short pawls g of the outer pawl-ring G engage the ratchet-teeth of the outer thread-guide-carrier ring F⁶, and the long pawls g' of said outer pawl-ring extend over the inner pawl-ring G and engage the ratchet-teeth of the inner thread-guide-carrier ring F⁷, and springs 80 and 81 operate to hold said pawls in contact with their respective thread-guide-carrier rings. The short pawls g² of the inner pawl-ring G' engage the ratchet-teeth of the inner thread-guide-carrier ring F⁷, and the long pawls g³ of said inner pawl-ring extend over the outer pawl-ring G and engage the ratchet-teeth of the outer thread-guide-carrier ring F⁶. Springs 81 operate to hold said inner pawls in contact with their respective thread-guide-carrier rings, the long pawls of each pawl-ring extending over the adjacent pawl-ring.

The pawl-rings G and G' are given rotary reciprocatory motion in opposite directions to each other by any suitable mechanism for that purpose. Referring to Fig. 13, when the outer pawl-ring G is moved toward the left in the direction of the point 1 of its arrow the inner pawl-ring G' is simultaneously moved oppositely in the direction of the point 2 of its arrow, and the effect of these opposite movements in the directions stated of these pawl-rings is that the shorter pawls g of the outer pawl-ring G engage the thread-carrier ring F⁶ and move it toward the left in the direction of its arrow and the short pawls g² of the inner pawl-ring G' engage the thread-carrier ring F⁷ and move it in the direction of its arrow toward the right, the long pawls of both pawl-rings sliding loosely over the teeth of their respective thread-carrier rings.

When the motions of the pawl-rings $G G'$ are reversed and the pawl-ring G moves in the direction of the point 3 of its arrow and the pawl-carrying ring G' moves in the direction 5 of point 4 of its arrow, the long pawls g' of the outer pawl-ring G engage the thread-carrier ring F^7 and move it in the same direction toward the right in which it was moved before, and the long pawls g^3 of the inner pawl-ring 10 G' engage the thread-carrier F^6 and move it in the same direction toward the left in which it was moved before, both sets of short pawls in this instance sliding freely over the teeth 15 of the thread-carrier rings without action thereon. The shifting of the motion of the pawl-carrier rings simply produces the alternation of the action of the pawls on the respective rings, the result being the intermittent rotary motion of the outer and inner 20 thread-carrier rings, respectively, in the same direction and in opposite directions to each other, so that the thread-guides move intermittently or step by step in opposite directions to each other and produce thereby the 25 proper formation of the knitting-strokes in connection with the needles, presser-ring, and sinkers.

The rotary reciprocating motion which is imparted to the pawl-carrying rings $G G'$ is 30 produced by means of two pattern-wheels $G^2 G^3$, which are clearly shown in Figs. 14 and 15 and which are eccentric to a vertical shaft S^4 , which is hung by an enlarged head to the upper pattern-wheel G^2 and guided in a 35 hanger-plate G^4 , that is attached to the under side of the main guide-ring F^8 , as shown in Fig. 14. On the hanger-plate G^4 are guided frames $G^5 G^6$, having angular flanges at their ends, the flanges of the frame G^5 being provided with protruding antifriction-points 40 90 and 91, that engage the circumference of the pattern-wheel G^2 , and the flanges of the frame G^6 being provided with antifriction-points 92 and 93, which engage the wheel G^3 . The circumference of each pattern-wheel is made 45 smooth for one half its length, while the other half of its length is made undulating. From the slide-frames $G^5 G^6$, which are reciprocated by the pattern-wheels and which are arranged 50 one below the other, extend angular arms 94 and 95 on the frame G^5 and 96 and 97 on the frame G^6 , that pass through openings in the bottom of the main guide-ring F^8 and are rigidly connected to the under side of the pawl-carrier rings $G G'$, as shown in Figs. 14 and 55 16. The angular arms are screwed to the flanges of the slide-frames $G^5 G^6$ and form thereby a rigid connection between them and the pawl-carrier rings, they being guided by 60 suitable openings in the hangers, so that a perfectly steady motion is imparted to them. To the lower part of the shaft S^4 is splined a ratchet-wheel G^7 , which is supported in a 65 looped frame 100, that is attached by means of curved hangers G^9 to the top ring A^2 of the supporting-frame A , as shown in Figs. 16, 17, and 18. The ratchet-wheel G^7 is engaged by

a pivoted spring-pawl G^{10} , that is applied to a double arm G^{11} , that is strapped around the shaft respectively above and below the 70 ratchet-wheel G^7 and connected at its outer end to the forked end of a connecting-rod G^{12} , the opposite end of which is pivoted to an intermediate oscillating elbow-lever G^{13} , that is pivoted in a suitable manner to the supporting-frame and provided at the outer end with an antifriction-roller G^{14} , that is acted upon by an eccentric-cam G^{14} on one of the auxiliary shafts S^6 , to which rotary motion is transmitted from the main driving-shaft S by the 75 vertical shaft S^7 and bevel-gearing R in any suitable manner. A helical spring G^{15} , applied to the double arm G^{11} , keeps the antifriction-rollers in contact with the face of the cam G^{14} and produces by the action of the 80 latter the oscillating motion of the pawl and thereby the step-by-step forward motion of the ratchet-wheel G^7 and of the pattern-wheels $G^2 G^3$, applied to the shaft S^4 of the ratchet-wheel G^7 . The intermittent rotary 85 motion that is imparted to the eccentric pattern-wheels moves the pawl-carrier rings in opposite directions until one half of the rotation of the pattern-wheels is accomplished. During the remaining half of the rotation of 90 the pattern-wheels the motions of the pawl-carrier rings are reversed, both rings, however, always moving in opposite directions to each other. One half of each pattern-wheel is divided into steps, of which ten are preferably arranged to correspond to the ten needles in each needle-carrier, so that each half-revolution of the pattern-wheels moves the pawl-carrier rings, and thereby the two sets of thread-guides, step by step over ten needles 95 in opposite directions to each other. The remaining half of the revolution of the pattern-wheels produces the reverse motion of the pawl-carrier rings and by the action of the 100 pawls before described the step-by-step motion of the two sets of thread-guides in continuous but opposite directions to each other for another ten needles, and so on. The eccentric portions of the pattern-wheels are arranged on the shaft in opposite directions to 105 each other, so that the described motion can be accomplished. The lower end of the shaft S^4 is grooved and splined to the hub of the ratchet-wheel G^7 for the purpose of providing for the up-and-down motion of the shaft S^4 110 in connection with the vertically-reciprocating motion of the main guide-ring F^8 , said splined connection of the ratchet-wheel and shaft being shown in Fig. 17.

The bobbins.—The threads by which the 115 tubular web is produced are supplied to the eyes of the upper and lower thread-guides F and F' from two series of bobbins $H H'$, that are arranged, respectively, on bearings of upper and lower bobbin-rings $B B'$, the ring B' 120 being arranged on the circular top plate A^2 on the supporting-frame, while the lower ring B is supported on inwardly-projecting brackets a' of the outer standards A' , as shown in

Fig. 2. The outer circumference of the bobbin-rings B B' are toothed, so as to be engaged by motion-transmitting pinions $h^2 h^3$, one for each bobbin-ring, as shown in Fig. 2, to which 5 rotary motion is imparted from the main driving-shaft S by means of the auxiliary shafts S^2 and eccentric cams h^4 , keyed to said shafts S^2 . To the eccentric cams are strapped arms h^5 , which are pivoted at their outer ends to 10 oscillating brackets h^6 , which carry pivoted and spring-actuated pawls h^7 , which engage ratchet-wheels h^8 , as shown in Fig. 20. To the shafts h^9 of the ratchet-wheels h^8 are 15 keyed the motion-transmitting pinions $h^2 h^3$, by which the intermittent step-by-step rotary motion is imparted to the bobbin-rings B and B', and thereby to the bobbins H H', supported on the same. The bobbins are made of comparatively large size and receive a certain 20 number of threads sufficient to supply a number of thread-guides, the bobbins in the drawings carrying, for instance, two hundred and four threads for the upper thread-guides and a corresponding number for the lower thread-guides. The threads are wound on the bobbins in the usual manner and conducted to the thread-guides over tension-rods $h^{11} h^{12}$, 25 that are supported by frames h^{13} and h^{14} , respectively, which are placed loosely on the spindles of the bobbins and connected at their 30 lower ends to tension-springs h^{15} and h^{16} , as shown clearly in Figs. 1, 2, and 3. Connected to the frames of the tension-rods are spring-pawls h^{17} and h^{18} , that engage ratchet-wheels h^{19} and h^{20} on the bobbin-spindles, so as to 35 impart a positive motion to the bobbins while the threads are supplied to the thread-guides and needles. The tension-frame h^{13} follows the tension exerted by the threads on the 40 same until the pawl h^{17} strikes against a stop h^{21} on the supporting-bracket of the bobbins, which causes disengagement of the pawl from the ratchet-wheel, so that the tension-frame is moved under the action of its spring into 45 upright position again, whereby the pawls engage the teeth of the ratchet-wheel and impart again a positive motion to the bobbins as required by the feed of the thread-guides and needles. The pawl h^{18} also engages a 50 similar stop h^{22} .

The tension-springs h^{15} are passed around the pulleys h^{23} and attached by their ends to the sleeves h^{24} , that are clamped by set-screws h^{25} to graduated arms h^{26} , applied to the bobbin-ring, as shown in Fig. 1, at the part where the bobbin is broken away, so that by the adjustment of the sleeve on the graduating-arm the degree of tension of the spring is regulated more or less, as required by the stiffness of 55 the goods. The tension-springs h^{16} for the lower bobbins are preferably connected directly to the graduated rod h^{27} , as shown in the lower part of Fig. 2.

By the tension-springs described bobbins 60 of comparatively large size respond quickly and accurately to the play of the threads and feed the same as required to the knitting

parts. The motions of the bobbin-rings are so timed that said rings move with the thread-guides around the needles and keep thereby 70 the upper bobbin-ring in one direction and the lower bobbin-ring in the other direction, so that they are always at their proper relative positions to the thread-guides by which the thread is supplied to the needles. The 75 tubular fabric that is knit by the machine is drawn in downward direction by weights, and after a certain quantity is knit the fabric is taken up by means of plates i , that are bent at their upper ends and attached by means 80 of a sleeve to the vertically-reciprocating sinker-ring-carrying rods e . The fabric is pressed against these plates by means of rollers i' and by means of brackets i^2 , that are attached to the exterior standards A' , said 85 rollers being provided with ratchet wheels that are engaged by spring-actuated pawls i^3 , which prevent the rollers from moving backward. During the downward motion of the rods e the plates i likewise move in downward 90 direction and take the fabric along by the friction exerted on the fabric by the plates i and rollers i' . When the rods e and the plates i are moved in upward direction, the rollers i' are retained by the pawls i^3 , so as to be prevented 95 from turning on their axes, whereby the tubular fabric is prevented from sliding in upward direction. One of the plates i is provided with a slitting-knife K , by which the tubular fabric is cut open at one point of 100 its length, so as to permit its removal from the machine.

The driving-shafts $S^2 S^3$ are preferably enclosed by suitable sheet-metal casings that act as a guard to prevent the soiling of the 105 fabric by contact with the same.

When a suitable length of fabric has been knitted—say twenty to twenty-five yards—it is pulled out sidewise and cut off in the manner well known to knitters.

When a suitable length of fabric has been knitted—say twenty to twenty-five yards—it is pulled out sidewise and cut off in the manner well known to knitters.

The operation of knitting the fabric will now be described. The different positions assumed by the devices directly connected with the formation of the stitches during the operation are best illustrated in Figs. 26 to 115 31, and the positions of the threads in connection with the needles and guides during said operation are illustrated in Figs. 32 to 34. In these figures a portion of the fabric x , which has already been knit, hangs by its 120 uppermost series of loops 3 on the needles 10, and knitting-threads marked 1 and 2, respectively, are connected to said fabric and extend out through the thread-guides to the spools, there being two such threads for each 125 needle. At the beginning of the formation of the new stitch or loop the loop forming or knitting devices are in the relative positions indicated in Fig. 26, the needles, as 10, being at their outmost limit, the sinkers, as E^3 , in 130 inward and downward position, the presser-ring D in its upward position, and the thread-guides F F' in upward position above the plane of the needles. The thread-carrier

5 rings F⁶ F⁷ are then moved by means of the rack-and-pawl mechanism for the distance of one tooth, and said thread-guides F F' are thereby shifted horizontally in opposite directions in a plane above the needles. This movement lays the threads 1 and 2 in opposite directions across the shanks of the needles, as shown in Fig. 32. Then by the downward motion of the main guide-ring F⁸

10 10 said thread-guides are moved in vertical direction, passing between the needles and assuming a position below the needles, as shown in Fig. 27. The needles remain at their outermost limit and the sinkers remain at their inner and lower position, holding the knitting fabric below the needles. The needles, their beards 11 being open, then move inward a partial stroke and cause the crossed threads 1 and 2, lying over the needles, to pass under 15 the open beards. The uppermost loops 3 of the fabric already formed which are impaled on the needles are prevented from being carried inward on the inward movement of the needles by contact with the sinkers E³. The needles then make a short dwell or stop and the presser D comes down upon the beards 11 and closes them by depressing their points into grooves in the shanks of the needles. The needles on this partial inward stroke stop 20 before the points of the beards pass inward to or beyond the notch or recess in the sinkers, as otherwise the impaled loops 3 would pass under the beards. At or about the same time that the needles make this partial inward stroke the sinkers E³ rise to permit the loops 3, impaled on the needles, to ride upward over the closed beards. The parts are then in the positions shown in Fig. 28. Then the sinkers move outward and upward to the 25 position shown in Fig. 29, and the presser D remains in contact with the beards and holds them closed. This movement of the sinkers pushes the impaled loops 3 of the fabric already formed over the points of the closed beards and starts them on their upward ride over said closed beards, the parts being then in the positions illustrated in Figs. 29 and 33. Then the presser D rises and releases the beards 11 of the needles 10, and the needles 30 resume their inward movement and assume the position indicated in Fig. 30, casting off the loops 3 over the bearded ends of the needles. These loops fall onto the threads 1 and 2 between their points of crossing through the needle-beards and the thread-guides, and new loops are thus formed which are impaled on the needles until a succeeding set of loops is knit in the same manner. Then the sinkers E³ are lowered to the position 35 shown in Fig. 31, pulling down the fabric on the new loops. The needles are then moved outward a full stroke, the sinkers moved inward and downward, and the thread-guides moved upward into the initial position shown 40 in Fig. 26.

The fabric α (shown in Figs. 32 to 34) is the simplest form that can be made on the ma-

chine; but this can be varied to some extent when heavier fabrics are required, in which case the motion of the thread-guides is slightly varied, which is produced by changing the shape of the pattern-wheels, by which motion is imparted to the thread-guides. These variations, however, are well known to the practical knitter, who simply changes the pattern-wheels when light, medium, or heavy fabrics are produced.

I claim as my invention—

1. The combination of reciprocating needles, a vertically-reciprocating presser-ring above said needles, vertically and horizontally reciprocating sinkers below the needles, upper and lower thread-guides, and means for raising and lowering and intermittently shifting said thread-guides. 85

2. The combination of reciprocating needles, a reciprocating presser-ring above the needles, a vertically-reciprocating sinker-ring, horizontally-reciprocating sinkers in said ring, upper and lower thread-guides, and means for vertically reciprocating and intermittently shifting said thread-guides. 90

3. The combination of reciprocating needles, a vertically-reciprocating presser-ring above said needles, a vertically-reciprocating sinker-ring below said needles, horizontally-reciprocating sinkers guided in said sinker-ring, two sets of thread-guides, a mechanism for imparting intermittent or step-by-step rotary motion to said thread-guides in opposite directions to each other, and mechanism for imparting a vertically-reciprocating motion to said thread-guides. 95

4. The combination of a circular series of knitting needles, means for reciprocating said needles, a vertically-reciprocating presser-ring above said needles, vertically and horizontally reciprocating sinkers below said needles, two sets of thread-guides, guide-rings on which the thread-guides are mounted, means for intermittently moving said guide-rings and the thread-guides mounted thereon in opposite direction around the circular series of needles, and means for vertically reciprocating said guide-rings and said thread-guides supported thereon. 105

5. The combination of two sets of thread-guides, guide-rings for supporting said thread-guides, said guide-rings having ratchet-teeth, a ring-shaped guide-frame for said rings, two pawl-carrier rings one for each guide-ring, pawls arranged in pairs on each pawl-carrier ring, a driving-shaft, a cam on said shaft, a mechanism between said cam and the pawl-carrier rings by which intermittent or step-by-step rotary motions in opposite directions are imparted to the guide-rings and thread-guides. 115

6. The combination of a circular series of reciprocating needles, a main guide-ring extending around said needles, two independent thread-guide-carrier rings guided in ways of the main guide-ring, two sets of thread-guides fixed to said thread-guide-carrying rings, two 130

pawl-carrier rings one for each thread-carrier ring each provided with pawls arranged in pairs and adapted to engage the ratchet-teeth of both thread-guide-carrier rings, means for imparting intermittent or step-by-step rotary motion in opposite directions to said pawl-carrier rings, and means for intermittently raising and lowering the main guide-ring whereby a vertically-reciprocating motion is imparted to the thread-guide.

7. The combination of two sets of thread-guides, thread-guide-carrier rings, a guide-ring in which the thread-guide-carrier rings are mounted, pawl-carrier rings arranged in said guide-ring inside of the thread-guide-carrier rings, said pawl-carrier rings being each provided with pawls arranged in pairs and adapted to engage the ratchet-teeth of the thread-guide-carrier rings, means for imparting an intermittent or step-by-step rotary motion to said pawl-carrier rings alternately in opposite directions whereby a continuous step-by-step motion is imparted to the thread-guide-carrier rings, and means for imparting a vertically-reciprocating motion to the guide-ring and hence to the thread-guides.

8. The combination of a circular needle bed-plate, a circular series of movable needle-carriers arranged in said bed-plate and provided with inwardly-extending shanks, groups of needles arranged in said carriers, and means for operating said needle-carriers, said means embracing horizontal bell-crank levers, and an oscillating ring concentric with said bed-plate for actuating said levers.

9. The combination of a circular needle bed-plate, a circular series of movable needle-carriers guided in said bed-plate and provided with inwardly-projecting shanks, groups of needles arranged in said carriers, means for operating said needle-carriers, said means embracing horizontal bell-crank levers, and an oscillating ring engaging said bell-crank levers, a cam on the driving-shaft, and a lever connected to said cam and said oscillating ring.

10. The combination of a vertical driving-shaft provided with cams, an annular needle bed-plate surrounding said shaft, needle-carriers disposed in groups and guided in said bed-plate and provided with shanks, a mechanism between one of said cams and said shanks imparting a reciprocating motion to the same, a sinker-ring below the needle bed-plate, sinker-carriers arranged in groups and guided in said sinker-ring, a mechanism between the second cam and the sinker-carriers imparting a reciprocating motion to said sinker-carriers, and a mechanism by which a vertically-reciprocating motion is imparted to the sinker-ring.

11. The combination of a vertical driving-shaft provided with two cams, an annular needle bed-plate surrounding said shaft, needle-carriers disposed in groups and movable in said bed-plate, groups of needles in said needle-carriers, a mechanism between said nee-

dle-carriers and one of the driving-cams for imparting reciprocating motion to said carriers, a presser-ring above said needles, means for imparting vertically-reciprocating motion to said presser-ring from the driving-shaft, a sinker-ring below the needles, means for imparting vertically-reciprocating motion to said sinker-ring, sinker-ring carriers arranged in groups and guided in said sinker-ring, a mechanism between said sinker-ring carriers and the lower cam on the driving-shaft for imparting a reciprocating motion to said sinkers.

12. The combination of a circular needle bed-plate, a circular series of reciprocating needles on said bed-plate, a vertically-reciprocating presser-ring above said needles, a vertically-reciprocating sinker-ring below said bed-plate, a series of horizontally-reciprocating sinkers guided in said sinker-ring, two sets of thread-guides, means for imparting a vertically-reciprocating motion to said thread-guides, means for imparting an intermittent or step-by-step motion to said thread-guides in opposite direction to each other, and intermittently-movable bobbin-rings carrying bobbins respectively for the upper and lower thread-guides, said bobbins moving with their corresponding thread-guides in opposite directions to each other.

13. The combination of a stationary needle bed-plate, a circular series of reciprocating needles guided in said bed-plate, a vertically-reciprocating presser-ring above said needles, a vertically-reciprocating sinker-ring below said needles, horizontally-reciprocating sinkers guided in said sinker-ring, two sets of thread-guides, a vertically-reciprocating main guide-ring, two carrier-rings for said thread-guides, and means for imparting an intermittent step-by-step motion to said carrier-rings in opposite directions to each other, said carrier-rings being arranged in sections, each one being operated independently of the other with the corresponding group of thread-guides supported thereon.

14. In a knitting-machine, the combination of a circular needle-bed provided with radial ways, a series of needle-slides movable in said ways, a series of needle-carriers connected with each needle-slide, each needle-carrier being adapted to receive a series of needles, and means for imparting a reciprocating motion to said slides.

15. In a knitting-machine, the combination of a needle bed-plate provided with an exterior ring having radial grooves and an interior ring connected with the exterior ring and provided with a less number of radial grooves, a series of needle-carriers the shanks of which slide in the radial grooves of the outer ring, each needle-carrier carrying a series of needles a series of needle-slides having radial shanks adapted to slide in the radial grooves of the inner ring, a series of needle-carriers being connected with each of said needle-slides, and means for reciprocating said needle-carriers.

16. In a knitting-machine, the combination of a needle bed-plate provided with an outer ring having radial grooves, and an inner ring provided with a less number of radial grooves, a series of needle-carriers, the shanks of which slide in the radial grooves of the outer ring, each needle-carrier carrying a series of needles, a series of needle-slides having radial shanks adapted to slide in the radial grooves of the inner ring, a series of needle-carriers being connected to each needle-slide, an actuating reciprocating ring, bell-crank levers pivoted to said bed-plate and connected with the shanks of said needle-slides and said reciprocating ring, and means for reciprocating said ring.

17. In a knitting-machine, the combination of a sinker-ring provided with radial grooves, sinker-slides having shanks adapted to move in said grooves, sinker-carriers vertically adjustable on said sinker-slides, each carrying a group of sinkers, means for reciprocating said sinker-slides, and means for raising and lowering said sinker-ring.

18. In a knitting-machine, the combination of a sinker-ring provided with an outer ledge, having radial grooves, and an inner ledge having a smaller number of radial grooves, sinker-slides having shanks adapted to slide in the grooves of the outer ledge, sinker-carriers vertically adjustable on said sinker-slides, and adapted to carry a series of sinkers, actuating-slides having shanks adapted to slide in the grooves of the inner ledge, said actuating-slides having each a series of sinker-slides connected therewith, means

for reciprocating said actuating-slides, and means for raising and lowering said sinker-ring.

19. In a knitting-machine, the combination of a sinker-ring provided with an outer ledge having radial grooves, and an inner ledge having a smaller number of radial grooves, sinker-slides having shanks adapted to slide in the grooves of the outer ledge, sinker-carriers vertically adjustable on said sinker-slides, and adapted to carry a series of sinkers, actuating-slides having shanks adapted to slide in the grooves of the inner ledge, said actuating-slides having each a series of sinker-slides connected therewith, bell-crank levers pivoted to said sinker-ring and adapted to engage the inner ends of the shanks of said actuating-slides, a reciprocating ring for actuating said bell-crank levers, and means for reciprocating said reciprocating ring.

20. In a circular-knitting machine, the combination of a circular series of needles, a circular series of sinkers operating in connection with said needles, and a thread-guide-carrier ring surrounding said needles and sinkers and constructed in detachable sections, and means for actuating said carrier-ring.

In testimony that I claim the foregoing as my invention I have signed my name in presence of two subscribing witnesses.

ARTHUR E. LINDNER.
